CLAIM

The ornamental design for a sound device, as shown and described.

DESCRIPTION

FIG. 1 is a top, front perspective view of a sound device, showing my new design.

FIG. 2 is a top plan view thereof.

FIG. 3 is a bottom plan view thereof.

FIG. 4 is a front view thereof.

FIG. 5 is a back view thereof.

FIG. 6 is a side view thereof; and,

FIG. 7 is an opposite side view thereof.

The broken lines in the figures illustrate the portions of the design that form no part of the claimed design.
